INSECT TRAP

Arthur A. Hill, Los Angeles, Calif., assignor to Hillmart Enterprises, Inc., Los Angeles, Calif., a corporation of California

Filed July 13, 1966, Ser. No. 3,072

Term of patent 14 years

(Cl. D22—19)

FIG. 1 is a side elevation of an insect trap showing my new design;

FIGURE 2 is a top view of the insect trap;

FIGURE 3 is a bottom view of the insect trap; and FIGURE 4 is a sectional view of the insect trap taken generally along line 4—4 of FIGURE 1.

The dominant features of the design reside in the portions shown in full lines.

I claim:

The ornamental design for an insect trap, substantially as shown and described.
